BRAKE DRUM WEAR LIMIT GAGE

George L. Marshall, Warwick, and Irving M. Leven,
Providence, R.I., assignors to The Central Tool Com-
pany, Cranston, R.I., a corporation of Rhode Island

Filed Jan. 2, 1962, Ser. No. 68,165

Term of patent 3½ years

(Cl. D52—6)

FIG. 1 is a front elevational view of a brake drum wear limit gage showing our new design;

FIG. 2 is a right-hand side elevational view thereof;

FIG. 3 is a bottom view thereof;

FIG. 4 is a rear elevational view thereof;

FIG. 5 is a left-hand side elevational view thereof;

FIG. 6 is a top plan view thereof.

We claim:

The ornamental design for a brake drum wear limit gage, substantially as shown.
